UNITED STATES PATENT OFFICE

SARKES TARZIAN, OF PHILADELPHIA, PENNSYLVANIA, ASSIGNOR TO ATWATER KENT MANUFACTURING COMPANY, OF PHILADELPHIA, PENNSYLVANIA, A CORPORATION OF PENNSYLVANIA

VOLUME CONTROL

Application filed July 8, 1930. Serial No. 466,372.

My invention relates to radio receiving apparatus either of the superheterodyne or radio frequency amplifier types, in which are used multi-grid thermionic vacuum tube amplifiers, such as those of the screen or shield grid type, and in which are effected various controls, as for controlling the volume of reproduction of the signals, including speech and music.

10 In accordance with my invention, the magnitude of amplification of a screen grid tube amplifier is varied while maintaining the internal plate impedance or resistance of the tube substantially constant or permitting it 15 to vary within suitable limits, by simultaneously controlling or varying, preferably by uni-control, the plate voltage and either the magnitude of negative bias upon the control grid, or, and preferably, the magnitude of 20 the screen grid voltage.

Further in accordance with my invention, the magnitude of the signal input voltage impressed upon one of the tubes of the receiving system, particularly a tube controlled 25 as aforesaid, is varied or controlled in combination or association with the aforesaid dual control, particularly to maintain high quality of reproduction, which otherwise would or might be seriously affected, particularly in 30 the case of extreme reduction or amplification occasioned by strong signals.

Further in accordance with my invention, the control of plate voltage and of negative bias of the control grid or of screen grid voltage 35 may be effected upon each of a plurality of cascaded amplifier tubes; and further in accordance with my invention, at or in advance of the input of the first stage of tubes so cascaded and controlled there may be 40 simultaneously effected the aforesaid control of input signal voltage.

Further in accordance with my invention, during the control of screen grid voltage in any of the relations aforesaid, the ratio of the 45 screen grid voltage to the plate voltage may be varied or, and preferably, maintained at a suitable and definite magnitude.

My invention resides in a system of controls of the character hereinafter described 50 and claimed.

For an understanding of my invention and for an illustration of some of the forms it may take, reference is to be had to the accompanying drawings, in which:

Figs. 1, 2 and 3 comprise, respectively, 55 curves or graphs illustrating the characteristics of screen grid tubes.

Fig. 4 is a diagrammatic view of a superheterodyne receiving circuit involving controls of plate and screen grid voltages, and of 60 input signal voltage.

Fig. 5 is a diagrammatic view of a superheterodyne receiving system involving controls of plate voltage, negative bias upon control grid, and input signal voltage. 65

Referring to Fig. 1, there are shown characteristic curves of screen grid tubes in general, and particularly of the present UV 224. Radiotron type, normally operating with a negative bias of 1.5 volts on the control grid, 70 75 volts positive bias on the screen grid, and 2.5 volts upon the cathode heater. Abscissæ are plate voltages for all three curves, while ordinates are conductances, in micromhos, for the mutual conductance curve G_m , magnitudes of the factor of amplification for the curve M_u , and resistance, in megohms, for the curve Y_p of internal plate resistances of 75 the tube.

From Fig. 1 it will be noted that as the 80 plate voltage decreases the plate resistance decreases, as does also the amplification factor M_u , while the mutual conductance G_m remains substantially constant, which is in effect substantially constant amplification by 85 the tube when having an external plate load or impedance, as is necessary in practice.

In Fig. 2, for a tube similar to that to which Fig. 1 relates, abscissæ are screen grid voltages, while for the mutual conductance 90 characteristic G_m the ordinates are mutual conductances in micromhos; for the curve M_u the ordinates are magnitudes of amplification factor; and for the curve Y_p , internal plate resistance, the ordinates are resistances 95 in megohms. With the plate voltage maintained constant, say at a normal voltage of 180 volts, with decrease of screen grid voltage or positive bias, the mutual conductance or amplification decreases, while at the same 100

time the internal plate resistance of the tube increases.

In accordance with my invention by simultaneously and at suitably relative rates decreasing the plate voltage and the screen grid voltage, the mutual conductance or amplification may be very greatly reduced, for purposes of volume control or otherwise, while the internal plate resistance of the tube remains substantially constant or varies only between rather narrow limits, and in any case may be kept comparable to or within a relatively low ratio of magnitude with respect to the external plate impedance.

By the simultaneous control of the plate and screen grid voltages and in the same sense, the effect of decreasing internal plate resistance by decrease of plate voltage, Fig. 1, is offset or compensated for more or less completely or accurately by the increase in internal plate impedance, due to decrease in screen grid voltage, Fig. 2. In consequence, amplification may to great extent be varied with unimportant or small change in plate impedance.

In lieu of varying screen grid voltage for the purposes aforesaid the magnitude of negative bias upon the control grid may be varied along with variation of plate voltage with substantially like effect. This is illustrated by the characteristic curves in Fig. 3, where a tube of the same average characteristics contemplated by Figs. 1 and 2 has a plate voltage of 180 volts, 75 volts on the screen grid and 2.5 volts on the cathode heater. In this figure, abscissæ are negative bias voltages upon the control grid, the ordinates for the mutual conductance curve G_m are again mutual conductances in microhms, and for the amplification factor curve M_u the ordinates are magnitudes of that factor, and for the internal plate resistance curve Y_p the ordinates are resistances in megohms. As indicated, by decreasing the absolute voltage of the control grid, i. e., increasing the magnitude of negative bias thereon, the internal plate impedance rises, while the mutual conductance or amplification decreases. The curves Y_p and G_m of Figs. 2 and 3 accord, in kind or sense of variation, with those in Figs. 2 and 3. In general, the effect of increasing negative bias upon the control grid has the same effect upon increase in internal plate resistance and mutual conductance or amplification that obtains in event of decrease of screen grid voltage. Comparing Figs. 1 and 3, therefore, the effect of decrease of plate voltage upon internal plate resistance is offset by increasing the magnitude of negative bias upon control grid, so that while decreasing amplification, curve G_m of Fig. 3, the internal plate resistance is maintained constant or varies inconsequentially or unimportantly, and maintains roughly a given

relation or ratio to a given external plate impedance.

In Fig. 4 is illustrated one of various circuit arrangements in which the variation of plate and screen grid voltages is effected for greatly varying volume, as in volume control, or for other purposes, while maintaining the internal plate impedance of the tube reasonably constant.

Referring to Fig. 4, which illustrates the significant portion of a superheterodyne system, D is the first detector upon whose input electrodes, control grid and cathode, is impressed the radio frequency voltage representing the signal or message, including speech and music. In advance of this tube may be any suitable tuning or selective system for tuning to the frequency of the desired signal while discriminating against all other frequencies, including those which produce the same beat frequency by reaction with the locally generated oscillations. The generator of local oscillations is diagrammatically indicated at O, impressing the oscillations generated upon the input system of the detector D through the transformer t. The frequency of the oscillations produced by the generator O are varied to produce at all frequencies of desired signals the same beat or intermediate frequency.

The voltage of intermediate frequency, for example of the order of 130 kilocycles for present broadcast reception, appearing in the plate circuit of the detector D, is impressed upon the input system of the first screen grid intermediate frequency amplifier tube V, which amplifies the current of intermediate frequency. Its plate circuit is coupled to the input of a second like intermediate frequency amplifier tube V1 in whose plate circuit appears a current of intermediate frequency of still greater magnitude. That plate circuit is suitably coupled to the input of the second detector tube V2, which is coupled to a suitable audio frequency amplifier tube, or several of them in cascade, with the last of which, which may be a push-pull combination, may be associated a signal translating instrument, commonly a loud speaker.

In the vacuum tubes referred to, the control grids are indicated at g, screen or shield grids at s, the cathodes at c, (in these cases heated by the heaters h), and anodes or plates at A.

The source of power may be anything suitable or convenient, as direct current from a power line or battery, or, as illustrated, from an alternating current lighting or power system whose line conductors are indicated at 1 and 2. Across these conductors is the primary of a transformer T, having a secondary S1 associated with the double wave rectifier tube V3, having a filament or cathode f heated by current from the secondary

S2 for supplying the high voltage or plate circuit current in the form of rectified and filtered current, the filter system comprising usual inductances and capacities, as indicated. Secondary S3 supplies current to the cathode heaters *h*, or directly to filaments if used as cathodes. The terminals of the high potential source for the plate circuits of the tubes of the receiving system are indicated at 3 and 4, the latter generally at ground potential or at potential of the base or chassis of the receiving set, and 3 being the terminal between which and terminal 4 exists a difference of potential of say 160 volts. The direct current field winding of the signal translating instrument or electrodynamic loud speaker is indicated at F.

The plate circuits of the tubes D, V, and V1, are supplied through choke coils *b* or by any other suitable arrangement.

For the tubes V, V1, there is provided a potentiometer resistance P, of say 110,000 ohms connected between the high potential terminal 3 and the terminal 4 or, what is the same thing, the ground or chassis terminal E. The common lead 5 for the plate circuit supplies of the tubes V and VI, is connected to the contact 6 movable along the potentiometer resistance P, whereby the voltage impressed upon the plates *a* of the tubes V and V1 may be varied for the purposes herein described. The conductor 7 serves in common to the screen grids *s* of the tubes V and V1 for impressing thereon a suitable positive bias voltage, which is variable, with variation of the plate voltage for these tubes and in the same direction or sense. This is accomplished by connecting the conductor 7 to a point 8 of the resistance comprising the portions R and R1, connected in series between the aforesaid slider contact 6 and terminal 4 or ground E. As indicated, the connection at point 8 is permanent, resulting in a substantially fixed ratio between the screen grid and plate voltages of and for the tubes V and V1, whatever may be the plate voltage magnitude. For example, the sections R and R1 may have resistances of about 20,000 and 60,000 ohms respectively, whereby, throughout the variation of plate voltage for the tubes V and V1, the screen grid voltage will be about one-half thereof. It shall be understood that in any event by these or equivalent means, the screen grid voltage is, throughout the variation of the plate voltage, of such relative magnitude as to maintain the internal plate resistance substantially constant or within suitably narrow limits.

It will be understood, however, that at the end 8 of the conductor 7 may be a slider contact, movable along the resistance R, R1, to effect suitable variation of ratio of screen grid to plate voltages as they are varied together in the same direction or sense. Such

slider contact may be actuated through suitable mechanical connection in unison with contact 6 and any other contacts actuated in unison with the latter. Ordinarily, and preferably, a fixed connection 8 is utilized.

In the arrangement shown, the plate and screen grid voltages of the tubes in question are simultaneously varied by movement of the single contact 6. However, the screen grid voltage may be obtained by contact, at end 8 of conductor 7, movable along the resistance R, R1 when itself connected between the terminals 3 and 4, and that sliding contact and contact 6 are preferably mechanically united or adjusted in unison with or by uni-control of those contacts and any other controls that are united in a uni-control with contact 6.

The controls of the plate and screen grid voltages of the tubes V and V1 effect a wide range of variation of amplification, thereby producing a very large variation in the volume of reproduction by the signal translating instrument or loud speaker. For example, in event of strong signals, the volume of reproduction may be reduced to suitable or comfortable volume by reducing simultaneously the screen grid and plate voltages of these amplifier tubes.

There is provided a control of the input signal voltage, whereby, in case of unusually strong signals, the volume may be controlled by varying the screen grid or plate voltages of one or both of the tubes V and V1, and additionally by the signal input voltage control, the latter supplementing the former by a nice and fine control. The signal input control, in the example illustrated, is provided by shunting across the input of one of the tubes, as V, a variable portion of the resistance R2 of say 100,000 ohms connected to grid *g* of tube V and engaged by contact or slider 9 connected to cathode or ground. Again this contact or slider 9 is united mechanically for uni-control with the slider or contact 6, and any other sliders or adjustable elements united with the latter in uni-control. The mechanical connection or uni-control is indicated by the broken line 10. By moving the contact 9 upwardly, the effective voltage impressed upon the input of the tube V is decreased, thereby decreasing volume of reproduction.

Where very strong signals are encountered, as from nearby broadcasting stations, the screen grid and plate voltages and resistance R2 are simultaneously or in unison reduced. This reduces not only the effective input signal voltage but very greatly reduces also the amplification. While reduction of amplification by control of screen or control grid bias and plate voltage is in itself useful and effective, for very strong signals the control of screen or control grid bias and plate voltage would have to be carried to such an

extent sufficiently to reduce the amplification, that the amplifying tube would be compelled to operate upon that portion of its characteristic related to screen or control grid bias that 5 distortion, particularly of speech or music, would be introduced with a consequent loss of quality of reproduction. By using in combination the aforesaid control of input signal voltage, of the type illustrated by way of 10 example or of any equivalent type, the amplification need not be so rigorously reduced, and without loss of quality or introduction of distortion the volume may be further reduced by the signal input voltage control.

15 While the control of input signal voltage is effected in the example illustrated at the input of an amplifier tube whose amplification is controlled, it will be understood that the input signal voltage control may be located 20 at any other suitable position, preferably further in advance toward the antenna or absorption structure than indicated. In a superheterodyne system, it is preferred to control, as illustrated, the input voltage of the 25 intermediate frequency. It will be understood, however, that such input signal voltage control may be applied to the input of the first detector tube D or at any suitable point in advance thereof.

30 While it may suffice to control the screen grid and plate voltages of one amplifier tube, either V or V1, it is preferable to effect the dual control of grid bias and plate voltage upon two or more of the amplifier tubes because, in event of strong incoming signals, if 35 the volume control were confined to one or the first of the amplifier tubes only, to procure sufficiently low volume of reproduction, there would still exist very high amplification in 40 the second or later amplifier tubes, giving rise to tube noises. To avoid these tube noises, it is preferred to apply the amplification control to two or more of the amplifier tubes.

While the signal input voltage control may 45 also be duplicated at any suitable point in the system, it is preferred that but a single control of this type be utilized, and it is further preferred that it be applied to the first of the amplifying tubes whose amplification 50 is controlled. If, for example, a second input voltage control were applied to the second amplifying tube V1, there would result a reduction in the maximum amplifying power of the first tube or stage V. When located as 55 shown, in the output system of the detector D or the input system of the tube V, the control resistance R2 has little effect upon the tuning characteristics, as in the case illustrated wherein the output system of cascaded amplifier tubes there may be disposed a combination of inductance L and capacity C tuned to a narrow band within which lies the intermediate frequency. In these tuned coupling systems the tuned circuit resistance is low, 60 and the presence of any other substantial re-

sistance, as R2, would have a detrimental effect.

The following table is exemplary of what may be procured by variation of plate and screen grid voltages, with respect to internal plate impedance for five magnitudes of amplification or volume; maximum, first line, and minimum, last line, and three intermediate values. In columns 1 and 2 are given, respectively, the plate and screen grid voltages. In column 3 appear the corresponding internal plate impedances of the tube.

	1	2	3	80
Maximum	1 +160	+72	640,000	70
	2 +85	+42	390,000	
	3 +45	+22	360,000	
Minimum	4 +25	+12.5	730,000	75
	5 +10	+5	880,000	

It will be noted that the internal plate impedance of the tube varies within relatively narrow range between 360,000 and 880,000 ohms. The internal impedance varies from 640,000 ohms at maximum amplification, through other magnitudes, to 880,000 ohms at minimum amplification.

In the tuned loops L, C, Fig. 4, for an intermediate or beat frequency of say 130 kilocycles, with an inductance L fourteen millihenries, the capacity C will be about 120 micromicrofarads. Each of these tunable loops by itself or disconnected has at resonance a resistance of about 800,000 ohms across its terminals. Accordingly by the volume control described the internal plate resistance remains for practical purposes substantially of the same order of magnitude or less than the external plate impedance as viewed with respect to the tuned loop L, C.

In Fig. 5 the circuit arrangement is in general that of Fig. 4, like reference characters indicating corresponding parts in the two figures.

The input signal voltage control and plate voltage control are those of the character described in connection with Fig. 4. Their movable contacts 6 and 9 are mechanically coupled for operation in unison by the structure indicated at 10, which also operates the movable contact 11 slidable along the resistance R3 of say 150,000 ohms which, in the example illustrated, is in series between the terminals 3 and 4 of the high tension source with the resistance P. The three sliders or contacts 6, 11 and 9 are moved in unison, and in such sense that as the plate voltages upon the tubes V and V1, or either of them, are decreased, the negative bias upon the control grids g, or either of them, of the same tubes is increased. In the specific example illustrated, the slider contact 11 for this purpose will move upwardly while the slider 6 moves downwardly. Upward movement of slider 11 increases the positive potential of the cathode c with respect to control grid g which

in effect is an increase in the negative bias of the control grid, making that grid more and more negative as the slider 11 ascends on the resistance R3. At the same time the slider 9 is moved along the input signal control resistance R2 in suitable sense and at suitable relative rate for the purposes generally hereinbefore described.

The arrangement of Fig. 5 gives in general 10 the same results described in Fig. 4 as to variation of volume or control of amplification with small or insubstantial effect upon the magnitude of the internal plate resistance of the tube.

15 In general, what has been said hereinbefore of the various circuits, including Fig. 4, applies as well to Fig. 5.

In Fig. 5 the screen grid voltage is maintained substantially constant, and is obtained 20 by tapping the end 8 of the conductor 7 to a suitable point on the resistance whose components are R and R1, connected between the terminals 3 and 4, i. e., across the terminals of the high tension source, which is the arrangement described in connection with a 25 variant of Fig. 4. In the present instance, however, the screen grid voltage is not variable by the arrangement shown, and the end 8 of the conductor 7 constitutes a fixed tap upon 30 the resistance R, R1.

While generally not required, it may be understood, however, that the end 8 of the conductor 7 may be a slider upon the resistance R, R1, which may be varied or moved 35 either in unison with the contacts 6 and 11 and/or 9, either in a sense to give a cumulative effect with change in control grid bias, or an effect in opposition thereto.

My controls of the character hereinbefore 40 described are not limited in their application to superheterodyne receivers. They are applicable equally to other types of receivers using screen grid tubes, for example, in radio frequency amplifiers. Figs. 4 and 5 45 serve to illustrate such receivers, as well, since in any event the intermediate frequency is a radio frequency. This is exemplified by omitting the first detector D, and relating to the input electrodes of the then first radio 50 frequency amplifier tube V a suitable coupling with an antenna or other absorption structure including or not, as desired, one or more cascaded tuned circuits. In such case, the condensers C may be of fixed magnitude 55 tuning the radio frequency amplifier to a narrow band of frequencies, or, and generally, the condensers C will be variable for tuning to various frequencies within the broadcast or other range. It will be understood, however, 60 both as to superheterodyne receivers and radio frequency amplifiers, that types of coupling not involving combinations of inductance and capacity such as L, C, may be employed.

65 What I claim is:

1. In the operation of a radio receiving system comprising an amplifier tube of the screen grid type, a method of control which comprises carrying the plate voltage of the tube to effect a change in the internal plate resistance thereof, and simultaneously so varying the screen grid voltage of the tube as to offset said variation of internal plate resistance and to effect a substantial change in the amplification by said tube. 70

2. In the operation of a radio receiving system comprising an amplifier tube of the screen grid type, a method of control which comprises varying the plate voltage of the tube to effect a change in the internal plate resistance thereof, and simultaneously so varying the negative bias upon the control grid as to offset said variation of internal plate resistance and to effect a substantial change in the amplification by said tube. 75

3. In the operation of a radio receiving system comprising an amplifier tube of the screen grid type, a method of control which comprises varying the plate voltage of the tube to effect a change in the internal plate resistance thereof, simultaneously so varying the bias of a grid of the tube as to offset said variation of internal plate resistance and to decrease the amplification within the limit at which distortion occurs, and reducing the signal input voltage to a degree effecting distortionless reproduction of a magnitude less than that corresponding with said reduction of amplification. 80

4. In the operation of a radio receiving system comprising an amplifier tube of the screen grid type, a method of control which comprises varying the plate voltage of the tube to effect a change in the internal plate resistance thereof, simultaneously so varying the screen grid voltage of the tube as to offset said variation of internal plate resistance and to decrease the amplification within the limit at which distortion occurs, and reducing the signal input voltage to a degree effecting distortionless reproduction of a magnitude less than that corresponding with said reduction of amplification. 100

5. In the operation of a radio receiving system comprising an amplifier tube of the screen grid type, a method of control which comprises varying the plate voltage of the tube to effect a change in the internal plate resistance thereof, simultaneously so varying the negative bias of a control grid as to offset said variation of internal plate resistance and to decrease the amplification within the limit at which distortion occurs, and reducing the signal input voltage to a degree effecting distortionless reproduction of a magnitude less than that corresponding with said reduction of amplification. 110

6. In the operation of a radio receiving system comprising a tube of the screen grid type, a method of control which comprises 120

varying the plate voltage of the tube, simultaneously so varying the screen grid voltage of the tube that the internal plate resistance of the tube changes to an extent materially less than that caused by said variation of 5 the plate voltage, and maintaining substantially constant the ratio of the screen grid voltage to the plate voltage.

7. The combination with an amplifier tube of the screen grid type, of means for varying 10 the plate voltage, and means for simultaneously varying the bias voltage of a grid of said tube to vary the amplifying effect of the tube while preventing abnormal change in the internal plate resistance thereof.

15 8. The combination with an amplifier tube of the screen grid type, of means for reducing the plate voltage, and means for simultaneously reducing the screen grid voltage of said tube to reduce the amplifying effect of 20 the tube while preventing abnormal decrease in the internal plate resistance thereof.

25 9. The combination with an amplifier tube of the screen grid type, of means for reducing the plate voltage, and means for simultaneously varying the negative bias of a control grid to reduce the amplifying effect of the tube while preventing abnormal decrease in the internal plate resistance thereof.

30 10. The combination with an amplifier tube of the screen grid type, of means for varying the plate voltage, means for simultaneously varying the screen grid voltage of said tube to vary the amplifying effect of the tube 35 while preventing abnormal change in the internal plate resistance thereof, and means for maintaining substantially constant the ratio of the screen grid and plate voltages.

40 11. The combination with an amplifier tube of the screen grid type, of means for varying the plate voltage comprising a conductive impedance traversed by uni-directional current, means connecting with the plate of said tube for applying thereto voltages corresponding with different points on said impedance, and means for determining the ratio 45 of the screen grid voltage to the plate voltage comprising a conductive impedance in shunt with the variable portion of said first-named impedance, and a connection from a point intermediate the terminals of said second-named impedance to the screen grid.

50 12. The combination with an amplifier tube of the screen grid type, of means for varying the plate voltage comprising a conductive impedance traversed by uni-directional current, means connecting with the plate of said tube for applying thereto voltages corresponding with different points on 55 said impedance, and means for determining the ratio of the screen grid voltage to the plate voltage comprising a conductive impedance in shunt with the variable portion of said first-named impedance, and a connection 60 from a fixed point intermediate the terminals 65

of said second-named impedance to the screen grid.

13. In the operation of a radio receiving system comprising a tube of the screen grid type, a method of control which comprises 70 simultaneously varying the plate voltage of the tube and the biasing voltage of a grid of the tube in such senses and to such relative extents that the internal plate impedance of the tube is varied to an extent differing from that 75 caused by variation of the plate voltage alone.

14. In the operation of a radio receiving system comprising a tube of the screen grid type, a method of control which comprises 80 simultaneously varying the plate voltage of the tube and the biasing voltage of a grid of the tube in such senses and to such relative extents that for decrease of plate voltage and decrease of effect of the grid biasing voltage the internal plate impedance of the tube decreases.

15. In the operation of a radio receiving system comprising a tube of the screen grid type, a method of control which comprises decreasing the plate voltage of the tube, and 90 simultaneously decreasing the biasing voltage of a grid of the tube while decreasing the difference between the plate and grid biasing voltages, thereby decreasing the internal plate 95 impedance of the tube.

16. In the operation of a radio receiving system comprising a tube of the screen grid type, a method of control of amplification which comprises simultaneously varying the plate voltage of the tube and the biasing voltage of a grid of the tube cumulatively to effect 100 a variation of the mutual conductance of the tube and differentially to affect the ratio of the internal to the external plate impedance of the tube.

105 17. In the operation of a radio-receiving system comprising a tube of the screen grid type, a method of controlling the amplification or volume of reproduction which comprises simultaneously varying the voltages applied to the plate and a grid of the tube to vary the internal plate impedance of the tube through a range below the external plate circuit impedance.

110 18. In the operation of a radio receiving system comprising a tube of the screen grid type, a method of controlling the amplification volume of reproduction which comprises simultaneously varying the voltages applied to the plate and control grid of the tube to reduce the internal plate impedance of the tube below the external plate circuit impedance.

115 19. In the operation of a radio receiving system comprising a tube of the screen grid type, a method of controlling the amplification through a range, which comprises simultaneously varying the voltages applied to the plate and a grid of the tube, thereby varying 120 the internal plate impedance of the tube to 125 130

a magnitude higher, for a portion of said range, and to a magnitude lower, for another portion of said range, than the external plate circuit impedance.

20. In the operation of a radio receiving system comprising a tube of the screen grid type, a method of controlling the amplification through a range, which comprises simultaneously varying the voltages applied to the plate and screen grid of the tube, thereby 10 varying the internal plate impedance of the tube to a magnitude higher, for a portion of said range, and to a magnitude lower, for another portion of said range, than the external plate circuit impedance.

15 21. Radio receiving apparatus comprising a tube of the screen grid type, means for varying the plate voltage of said tube, and means for simultaneously varying the biasing voltage of a grid of said tube, in such senses and 20 to such extents that the internal plate impedance of the tube is varied to an extent differing from that caused by the variation of plate voltage.

22. Radio receiving apparatus comprising 25 a tube of the screen grid type, means for simultaneously varying the plate voltage of the tube and the biasing voltage of a grid of the tube in such senses and to such relative extents that for decrease of plate voltage and 30 decrease of effect of the grid biasing voltage, the internal plate impedance of the tube decreases.

23. Radio receiving apparatus comprising 35 a tube of the screen grid type, and means for controlling the volume of reproduction, adjustable for simultaneously decreasing the plate voltage and the biasing voltage of the grid of the tube to decrease the difference between the plate and grid-biasing voltages 40 thereby to decrease the internal plate impedance of the tube.

24. A radio receiving system comprising a 45 tube of the screen grid type, means for simultaneously varying the plate voltage and biasing voltage applied to a grid of said tube, a second tube subsequent to said first tube and of the screen grid type, and means for varying the screen grid voltage of said second tube simultaneously with the variation of plate and grid biasing voltages of said first tube by said first means.

SARKES TARZIAN.

CERTIFICATE OF CORRECTION.

Patent No. 1,885,307.

November 1, 1932.

SARKES TARZIAN.

It is hereby certified that error appears in the printed specification of the above numbered patent requiring correction as follows: Page 1, line 30, for "or" read "of"; page 7, line 26, claim 22, before "means" insert the word "and"; and same line, after "means" insert the words "for controlling the volume of reproduction, adjustable"; and that the said Letters Patent should be read with these corrections therein that the same may conform to the record of the case in the Patent Office.

Signed and sealed this 3rd day of January, A. D. 1933.

(Seal)

M. J. Moore,
Acting Commissioner of Patents.
